UNITED STATES PATENT OFFICE

KARL VIKTOR RUDIN, OF STOCKHOLM, SWEDEN

CALCULATING MACHINE

Original application filed June 30, 1922, Serial No. 571,943, and in Sweden July 1, 1921. Divided and this application filed May 29, 1924. Serial No. 716,755.

The invention relates to calculating machines of the kind in which the items before being thrown into the totalizing mechanism, are first set up in a selector mechanism mounted on a carriage and comprising selector members adapted to be set successively in accordance with the values of the keys depressed. One object of the invention is to provide a setting up mechanism, in which 10 the effort necessary to be expended for the setting operation is considerably reduced, thus rendering the machine capable of a high speed. This is attained, according to the invention, by reducing the stroke of the setting keys, at the same time ensuring a light touch of said keys. Another object is to provide a clear arrangement and a simple construction of said setting up mechanism. It is previously known to arrange the selector 15 members or wheels in such a manner that the normal angular position of said wheels corresponds to an intermediate value, as for instance 4 or 5, the wheels being then adapted to be turned in the one or the other angular direction, according as the value to be set up is higher or lower than the said intermediate value. Obviously, the greatest amount of rotation required to be imparted to a selector wheel for setting it up is reduced by this 20 arrangement to half of the rotation otherwise required, and, as a consequence, it is possible to reduce the key stroke in a corresponding degree. In the said known arrangement, however, it is necessary, on actuating the selector wheel to be set up, to rotate as a whole the group of selector wheels which have not yet been set up. The said disadvantage is avoided, according to this invention, by a suitable combination of the escapement mechanism of the selector carriage with the setting up member which is provided for conveying the motion imparted to the key depressed to the selector wheel to be set up. The said escapement mechanism and the said 25 setting up member are adapted to co-operate so as to make it possible to actuate the selector wheel in turn to be set up independently of the other wheels and, further, to release the setting up member, on completion of the setting movement, from its constrained connec-

tion with the selector wheel and, finally, to return it to normal position. This invention is a division of my copending application for Letters Patent of the United States for improvements in calculating machines, filed 55 June 30, 1922, Serial No. 571,943.

The invention will be more closely described with reference to the accompanying drawings which illustrate some embodiments of the invention. In the drawings 60

Fig. 1 is a plan view of a calculating machine representing a practical embodiment of the invention, the cover plate thereof being removed.

Fig. 2 is a part of a longitudinal section 65 on the line III—III in Fig. 1.

Fig. 3 shows a modification of a detail in Fig. 2.

Fig. 4 is a detail of the escapement mechanism. 70

Fig. 5 is a detail of Fig. 2.

Fig. 6 is a detail of Fig. 2.

Fig. 7 shows a modified form of the key stems.

Fig. 8 is a side elevation of a modified form 75 of the segmental rack gearing shown in Figs. 2 and 5.

Fig. 9 is a slightly more detail showing of Fig. 8.

Referring to Figs. 1-and 2, the detailed 80 description of the machine will comprise only those parts thereof which constitute the invention, whereas other parts thereof which are provided to co-operate directly with the parts first mentioned will be mentioned more briefly. The setting up mechanism is arranged to the right of the machine under the ten setting keys 1 to co-operate therewith. The selector carriage consists of a yoke 18, the shanks 18' of which are slidably 85 mounted on a shaft 14 so as to embrace the selector wheels 15 which are loosely mounted on said shaft 14. The number of selector wheels in the example shown is nine. The carriage, which normally occupies the position illustrated in Fig. 1 at the right of the shaft 14 is adapted to be moved leftward step by step during the setting operation, the selector wheels set up being thereby aligned 90 with corresponding digit wheels of the to- 95 100

talizing mechanism. The highest digit of the item to be thrown into the machine will be set up on the first selector wheel at the left of the group, the next digit on the second 5 wheel and so forth. The totalizing mechanism consists of totalizer wheels 41 and intermediate gears 42, loosely centered on axles 45 and 48 respectively; both of which are mounted in the shanks 46' of a clamp 46 pivoted on a horizontal shaft 13 parallel to the shaft 14 of the selector wheels. A number of horizontal racks 43 running perpendicularly to the shaft 14 are provided to transfer the item set up on the selector wheels to the totalizing mechanism, the number of said racks being equal to the number of selector wheels. For said purpose the racks 43 are slidably mounted on transversal shafts running through longitudinal slots of the racks, the 20 rear one 51 of said shafts being firmly secured to the frame, whereas the other shaft is mounted on rocking arms and adapted to raise the front ends of the racks, on completion of the setting up operation, into engagement with the selector wheels. At the same time the totalizer wheels 41 or the intermediate gears 42, according as addition or subtraction is to be performed, are caused to mesh with the racks 43. The transfer of the 25 item is performed by the selector wheels set up, upon rotating the shaft 14, being returned to their normal positions, each of the racks meshing with said wheels being then withdrawn forwards in proportion to the numerical 30 value set up on the corresponding wheel. Obviously, the corresponding totalizer wheels 41 will be rotated in the same proportions by the racks, and, as a consequence, the item will be added to or subtracted from the sum 35 registered in the totalizer. The movements of the racks 43 are, furthermore, transferred to the printing mechanism by means of a toothed gearing meshing with the rear ends of the racks, the types corresponding to the 40 digit of the item being thereby set up in front of a printing roller. On completion of the transfer action the carriage is returned to its initial position at the right of the shaft 14. 45

A more thorough description of the totalizing mechanism and driving means of the machine will not be necessary, as these mechanisms are not specific to this invention, which may be applied in different combinations of parts in question, as will be understood from 50 the following disclosure. Having thus given a summary report on the parts of the machine which are adapted to co-operate with the setting up mechanism, I will now proceed to describe the essential features of the invention 55 more closely.

Each of the selector wheels 15, which are loosely mounted, as previously mentioned, on the shaft 14, consists of a cylindrical check disc of hard rubber carrying on its circumference the figures 0-9, and a gear firmly 60

connected therewith, said gear in the present case being provided with eleven teeth. Another number of teeth may as well be chosen, however, the circular pitch of toothing should be at most 1/10 of the circumference. In 70 the initial position of the selector carriage indicated in Fig. 1, the gear of the first selector wheel counting from the left of the carriage is aligned with a segmental rack 16 provided with eleven teeth and meshing said gear by 75 means of its middle tooth, provided no one of the setting keys 1 is depressed. The check discs of the selector wheels have a smaller diameter than the appertaining gears in order to make it possible to displace the 80 wheels axially on the shaft 14, without the discs being then touched by the segmental rack 16. The segmental rack is pivoted on a transversal shaft 17 and connected with the left end of a lever bar 11 arranged parallel 85 to the shaft 17, the right end of said lever bar being connected with an arm 16' (Fig. 1), which is likewise pivoted on the shaft 17. The lever bar 11 runs in front of the mouths of a series of slots 10 provided in the lower flat ends of the double armed key levers 5 which are pivoted on a common axle 6. The mouth of each of the key slots 10 is enlarged 90 so as to allow the bar 11 to be introduced into the slot to some extent without at first being engaged with the key lever. The other portion of each slot has a smaller width so as to positively engage the lever bar 11 on depression of the appertaining key, the segmental rack 16 being thus also positively connected 95 with the key. The end portions of each slot are curved to form circular arcs having a common centre located on the rotary axis of the key levers, while the lengths of their radius are different. The intermediate portion 100 of the slot on the other hand, is sloping, counting from below, either forwardly or rearwardly to cause the segmental rack to be turned in either direction depending on the 105 numerical value represented by the key depressed. As will be seen from this, the rotation of the segmental rack will not begin until the key has been depressed to some extent 110 and will cease before the depression of the key has been completed, the rack, however, on the further depression of the key, being positively locked in the set up position by the circularly curved end portion of the slot. The intermediate portions of the different slots 10 are sloping in different degrees in such a manner 115 that the actuation of any of the keys 1 to 5 will cause a rearward rotation of the segmental rack the amount of which is proportional to the numerical value represented by the key depressed, whereas on depression of any of the keys representing higher values 120 the rack will be rotated forwardly (rightwardly in Figs. 2 and 5). In the first mentioned case a rotation in the clockwise direction will be imparted to the selector wheel 125 130

which is just engaged by the segmental rack, the amount of said rotation depending on the numerical value being $1/11$ to $5/11$ of a full revolution. On the other hand, the depression of the 9-key will cause the selector wheel to be rotated in a direction reverse to the clockwise for $2/11$ of a full revolution, thus bringing the selector wheel in the same angular position, as if it had been rotated in the opposite direction for $9/11$ of a full revolution. By means of the 8-, 7- and 6-keys the selector wheel to be set up may correspondingly be rotated in the counter clockwise direction for $3/11$, $4/11$ and $5/11$ of a full revolution respectively. Fig. 5 shows by way of example the result of the depression of the 1-key. The upper arm 4 of each key lever is provided at its outer end with a notch 7, which is adapted to engage, in the final part of the key stroke, a transversal cam bar 8 extending between the segmental rack 16 and the arm 16' for the purpose of damping the elastic oscillations of the rack which might occur owing to the rack being suddenly stopped in set up position by the locking portion of the key slot 10.

In order to lock the segmental rack 16 in its normal position at rest a double locking means is provided on the lower, rearwardly extending arm 25 of a double-armed lever 24, Figs. 2, 6, which is pivotally mounted on a horizontal journal 29. Said lever arm has a recess 30 with a mouth opening downwardly which normally clutches the lever bar 11, said mouth being narrow enough to positively engage said lever bar thus preventing the segmental rack from being turned. Further, the arm 25 has an upwardly extending locking projection 31 normally engaging a notch 40 or the like on the periphery of the segment 16. The lever arm 25 is rigidly connected with a transversal bar 26 extending throughout the whole group of key levers close under said levers and adapted to be depressed alike by whatever key actuated. As a consequence, the means for locking the setting up member in its position at rest will be disengaged during the first part of the downward key stroke, as the lever bar 11 will then be received in the upper, enlarged part of the recess 30, while on the other hand the upper end of the projection 31 will leave the corresponding notch. At the same time the lever bar will be engaged with the sloping intermediate portion of the slot and will thus be positively connected with the setting up member. Owing to the selector wheel, which is in turn to be set up, being positively engaged by the segmental rack, the locking means provided for the setting up member will at the same time serve to hold the said wheel in position. In order to hold each of the selector wheels in its normal angular position until having been shifted leftward far enough to be engaged by the setting up mem-

ber there is provided a spline bar 19 extending along the right hand portion of the shaft 14, said spline bar having such a length as to engage, in the normal position of the carriage, the gears of the whole group of selector wheels excepting that of the first wheel at the left.

A further object of the lever 24 is to serve as a spacing lever adapted to cause the carriage to be displaced successively in axial direction, in such a manner that a divided escapement motion consisting of two steps will be performed during a complete actuation of any of the setting keys. For this purpose the upwardly extending arm of the lever 24 is provided with two sliding pawls 23 and 23' adapted to cooperate in a manner described below with a series of ratchet teeth 22 on the lower side of the carriage, Figs. 2 and 4, to bring about, upon operation of the lever 24, a stepwise lateral movement of the carriage. To this end the carriage is actuated by a coil spring 28 wound on a vertical spindle 33, said coil-spring tending to displace the carriage in a leftward direction through the intermediary of a pinion 21 firmly mounted on the spindle 33 and meshing with a rack bar 20 provided on the front edge of the clamp 18. The lateral displacement, however, is normally prevented by the pawl 23' engaging one of the ratchet teeth 22. Said pawl is yieldingly mounted on the arm 24 so as to allow of an unobstructed return movement of the carriage into its normal position at rest. The second pawl 23 is rigidly connected to the lever arm 24 so as to be normally out of path of the ratchet teeth 22. The pitch of the ratchet teeth 22 is equal to the length of the full escapement of the carriage, while the pawls 23, 23' are disposed at a distance apart, counting in the escapement direction, equal to half of said length. On the depression of any of the keys the pawl 23, owing to the rocking movement of the spacing lever 24, is brought in the path of the ratchet tooth just engaged by the yielding pawl 23', while at the same time the pawl last mentioned is gradually moved out of engagement with said tooth. At a certain instant, which is exactly adjusted with respect to the setting up movement, as will be more closely described below, the pawl 23' will slide off from the ratchet tooth, the carriage being then displaced laterally by the action of the coil-spring 28 until the same ratchet tooth strikes the pawl 23. As may be concluded from the foregoing description, this is not the full escapement action, but is only sufficient to cause the selector wheel just set up to be released from the segmental rack 16 which will thus be free to be returned to its normal position at rest. On the return stroke of the key the pawls 23 and 23' are again shifted, the carriage being thereby displaced another step leftward to bring the next se-

lector wheel into engagement with the segmental rack.

In order to make the mode of action of the setting up mechanism more clearly understood it may be assumed by way of example that the number 37 is to be set up for the purpose of being subsequently added to or subtracted from the total registered in the totalizer. The selector carriage originally occupies the position shown in Fig. 1 after having been returned to the right at the end of the foregoing calculation. On depression at first of the 3-key the normally acting lock of the segmental rack 16 will immediately be disengaged at the beginning of the key stroke, as described above. On the further depression the lever bar 11 is engaged by the sloping portion of the slot 10, the segmental rack being thereby turned rearwardly to an extent adapted to cause the first of the selector wheels, which originally is meshing therewith, to rotate for an angle of 3/11 of a full revolution in the clockwise direction (see Fig. 2). At the same time the pawl 23' which originally is in engagement with the first of the ratchet teeth 22, counting from the left, is moved rearwardly, owing to the turn of the spacing lever 24. The said pawl, however, will not slide off from the ratchet tooth, until the lever bar 11 has been received in the upper circular portion of the slot 10 thereby locking the segmental rack in the position set up. At the end of the downward key-stroke the first escapement step of the carriage has been performed, and the segmental rack is now free to be returned. Upon release of the key the key lever 5 will turn back to its initial position by the action of a coil-spring 12, the segmental bar being then withdrawn and also returned to normal position. At the same time the spacing lever 25 will turn back by the action of a spring wound on the journal 29 of said lever and, as a consequence, the pawl 23' is again brought in the path of the ratchet teeth, while the pawl 23 is sliding off from the first of said teeth at the end of the rear stroke of the key causing the second escapement step of the carriage to take place after the segmental rack has been locked in its normal position. At the end of the rear stroke the second selector wheel is occupying the setting up position meshing with the segmental rack, whereas the first selector wheel set up in an angular position corresponding to the numeral value 3 is alined with the first of the transmitting racks 43, counting from the right. In order to hold the selector wheels already set up in their different angular positions there is provided a spline bar 38 mounted on rocking levers and extending along the left hand portion of the shaft 14, said spline bar being of such a length as to clutch each of the selector wheels which have passed the setting up position. After the first digit of the number in question has now been set up,

the 7-key is depressed, the same process being then repeated, differing from that just described only by the segmental rack 16 being now turned forwardly, thus imparting an opposite rotation to the selector wheel, the rotary angle being in this case 4/11 of a full revolution. At the end of the rear stroke of the 7-key the second selector wheel will be alined with the first of the transmitting racks 43, whereas the first selector wheel will be in line with the second rack, counting from the right. The setting up operation is now completed. The transfer of the item to the totalizer is effected, as mentioned above, by zeroizing the selector wheels set up. For this purpose the shaft 14 is provided with a longitudinal row of zeroizing pins 156 (Fig. 1) arranged at a distance apart equal to a full escapement movement of the carriage. In order to make the selector wheels capable of passing said zeroizing pins on being displaced laterally each selector wheel is provided inside the hub with ten or eleven recesses 158 (Fig. 2) which are distributed circumferentially in such a manner that any of said recesses will be alined with the row of pins in whatever angular position the wheel be set up. On completion of a key actuation each of the selector wheels set up will be disposed over one of the zeroizing pins 156, said pin extending then in a circular groove inside the hub in which is provided a zeroizing abutment 157 (Fig. 2) adapted to co-operate with the pin. The zeroizing of the selector wheels is effected by the shaft 14 being rotated from the handle 38 on its forward stroke for 9/11 of a full revolution in a clockwise direction (Fig. 2). This rotary movement is transferred to the shaft through the intermediary of a suitable ratchet device, so that the shaft will be at rest during the rear stroke of the handle. The zeroizing abutments 157 of the wheels are arranged in such a manner relatively to the zeroizing pins 156, that each wheel will have a zeroizing rotation in proportion to the numerical value for which it is set up. As will be seen, the item set up will be properly transferred to the totalizer in the way described. After the transfer action has been completed the selector carriage is returned to normal position and is then ready for another operation. In the arrangement of the selector wheels described above the figures of the check discs are not quite distinctly displayed in corresponding check openings in the protecting cover of the machine because of the diameter of the cylindrical check discs being smaller than the outer diameter of the apertaining gears. In the arrangement shown in Fig. 3 the carriage is provided with particular check wheels 265 loosely mounted on a shaft thereon and allotted each to one of the selector wheels 15, each of said check wheels consisting of a check disc, carry-

ing figures on its cylindrical periphery, and a gear integral therewith and permanently meshing with the gear of the corresponding selector wheel 15. The diameter of the cylindrical check discs is equal to the outer diameter of the appertaining gears, so that the figures in this case may be distinctly displayed.

Fig. 7 illustrates a suitable modification of

10 the key stems, each of which is divided in two portions 267, 268 connected with one another by means of a coil-spring 269. This arrangement has for its object to prevent the parts of the mechanism from being hurt 15 in the case of two or more keys being unintentionally struck at a time, the yielding connections between the portions of the stems then serving as a protecting means.

As a further protective means a locking 20 device is provided for the purpose of preventing the handle 38 and the setting keys from being actuated at the same time, this locking device simply consisting of an arm 223 rigidly mounted on the shaft 59 of the 25 handle, said arm having a circularly curved projection 223', Fig. 6. The front end of the arc 223' is normally situated close to the free end of the rearwardly extending arm 25 of the lever 24, without obstructing the 30 free movement of said arm provided the handle is in its normal position at rest. At the beginning of a stroke of the handle the arc 223' will, however, be brought in the path of the lever arm 25, locking the arm in 35 its position at rest during the whole stroke. As a consequence, the setting keys are also locked, until the handle is returned to normal position. On the other hand, the rear end of the lever arm 25, on depression of a 40 key, will be moved in the path of the arc, thus locking the handle during the key action.

The modification shown in Fig. 8 differs from the arrangement according to Fig. 5 only by the single segmental rack 16 being substituted by two segmental racks 236, 237. The racks are pivoted on journals 238 and are connected with lever bars 239 which are adapted to co-operate each with a group of keys. In all other respects the lever bars 50 239 are adapted to be operated in the way described above for the lever bar 11. Obviously, all of the keys appertaining to either of the groups will actuate the selector 55 wheels in a common direction opposite to the direction specific to the other group. The segmental racks 236, 237 are normally pressed against studs 241 by means of coil-springs 240, being then, as shown in Fig. 8, completely out of path of the selector gears. By 60 this arrangement it is possible to make the diameter of the cylindrical checks discs equal to the outer diameter of the appertaining gears, so that the figures on the check discs may be distinctly displayed in the check 65 openings without providing particular check

wheels, as in the case of Fig. 3. The arrangement of two separate segmental racks has the further advantage that the total mass to be brought into motion at each key depression is greatly reduced. In the embodiment according to Fig. 8 the carriage escapement 70 may be effected in the same manner as in the embodiment first described.

I claim:

1. In a calculating machine a selector mechanism comprising in combination a number of adjustable selector members, a key operated setting up device adapted to engage said selector members independently of one another, and means associated with the keys for controlling the operation of said setting up device so as to cause the engaged selector members to be set each in accordance with the value of the corresponding key depression from an intermediate position in one direction by the operating of some of the keys and in an opposite direction by the operation of other keys. 75 80

2. In a calculating machine, a selector mechanism comprising in combination a number of adjustable selector wheels, mounted in carriage, a key operated setting up device adapted to engage said selector wheels separately in succession and means associated with the keys for controlling the operation of said setting up device so as to cause the engaged selector wheels to be set each in accordance with the value of the corresponding key depression from an intermediate position in one direction by the operation of some of the keys and in an opposite direction by the operation of other keys, said intermediate angular position coinciding with the angular position normally representing the numeral value zero. 95 100 105

3. A combination as claimed in claim 1, in which the setting up device consists of two racks, one of which is adapted to be operated by some of the keys, whereas the other rack is adapted to be operated by the other keys. 110

In testimony whereof I affix my signature.
KARL VIKTOR RUDIN.
